UNITED STATES PATENT OFFICE.

JOHN B. GRIFFIN, OF CHICAGO, ILLINOIS, ASSIGNOR, BY DIRECT AND MESNE ASSIGNMENTS, TO JULIA FRANCES GRIFFIN AND THOMAS H. KEEFE, BOTH OF SAME PLACE.

PEDAL BELL-SIGNAL DEVICE.

SPECIFICATION forming part of Letters Patent No. 396,868, dated January 29, 1889.

Application filed September 10, 1888. Serial No. 285,091. (No model.)

To all whom it may concern:

Be it known that I, JOHN B. GRIFFIN, a citizen of the United States, residing at Chicago, in the county of Cook and State of Illinois, 5 have invented a certain new and useful Improvement in Pedal Bell-Signal Devices, (Case 1,) of which the following is a full, clear, concise, and exact description, reference being had to the accompanying drawings, forming 10 a part of this specification.

It is common to provide upon street-cars, wagons, or buggies used in the fire-alarm service, and sometimes upon other vehicles, signal-bells, which are usually rung by pulling a 15 cord attached to the arm carrying the bell-hammer. In some cases a bell has been used upon the fire-marshall's buggy, which bell has been so arranged that it may be rung by pressure of the foot, a distinct movement of the 20 foot being required each time the gong is sounded. Thus in either case the constant attention of the one who is ringing the bell is required to keep it ringing. Such careful attention as is thus required is not always 25 consistent with the care and attention that may be required at the same time to drive the horses or, in the case, for example, of a grip-car, to drive the grip. In case of the 30 driver of a grip-car—as is generally known to those accustomed to this means of conveyance—he must use both hands at the same time, both in stopping and in starting. Therefore it is desirable to provide ready means for 35 continuously ringing the bell without the aid of the hands and with only such slight attention or volition of the driver as will not distract his attention from his other work. This I have accomplished by means of a pedal device connected with the arm or support for 40 the bell-hammer, in combination with radial projections upon the revolving axle, wheel, or hub of the car or vehicle, and so arranged that on pressing down the pedal the bell-hammer support will be brought in such relation to the 45 radial projections as to be vibrated thereby, to cause the hammer to strike the gong.

I preferably connect the pedal device with the bell-hammer support by a yielding connection—which may be any suitable spring or

elastic band—in order that the vibrations of 50 the hammer-support may not be communicated to the pedal, so as to be annoying to the driver.

In case of grip-cars I preferably arrange two sets of signal devices and provide for locking 55 one set in such position that it will not be in operative condition while the other bell-signal device is operative—that is to say, I so arrange the two sets of bell-signals that one will be operative when the car is going in one direction, while the other will be operative when the car is going in the opposite direction.

My invention is illustrated in the accompanying drawings, in which—

Figure 1 is a side elevation of two sets of 60 bell-signal devices applied to a grip-car, as seen from section-line X X of Fig. 3. Fig. 2 is a view illustrative of a modification of the spring or yielding connection between the 65 pedal and bell-hammer support. Fig. 3 is a 70 plan view of the grip-car shown in Fig. 1 provided with my invention. Figs. 4 and 5 are modifications of my invention, designed 75 more especially for fire-marshals' wagons. Fig. 6 is a front view of another style of grip-car, showing my bell-signal device applied thereto, the gong being placed near the roof of the car. Fig. 7 is a side elevation of my 80 bell-signal device, shown also in Fig. 6.

Like parts are indicated by similar letters 85 of reference throughout the different figures.

I will first describe my invention as illustrated in Figs. 1 and 3. It will be understood that the roof of the grip-car is removed and that the front and rear platforms are 85 shown broken away. I have not deemed it necessary to illustrate the gripping or driving mechanism of the car, this being a well-known construction and forming no part of my invention. It will be understood, further, that the driver stands at the center of the car when ears of the form shown in Figs. 1 and 3 are used. It is therefore in such case necessary to place the pedals near the center of the car, so as to be within reach of the 90 driver's foot. As these cars are designed to be driven in either direction, I have provided two sets of bell-signal devices, one set being

constructed to be operated by rotary motion in one direction, and the other set being constructed to be operated by rotary motion in the opposite direction. The car, we 5 will suppose, is moving in the direction indicated by the arrow in Fig. 1. The gong *a* is preferably placed, as shown, near the front of the car. The bell-hammer support *b* is pivoted, preferably as shown, to the floor of 10 the car and extends downwardly through the floor. The lower end of the bell-hammer support *b* is preferably weighted, so that it may ordinarily hang down in position to be out of 15 the path of the radial projections provided upon the axle. Upon the axle I provide the radial projections *c*. These projections may be in the form of wings, preferably placed at uniform distances apart and projecting radially, as shown. As shown in the drawings, 20 these wings are provided upon a sleeve which is adapted to be slipped over the axle and keyed thereto. It is obvious, however, that the construction of the radial projections is not material so long as they are adapted to 25 perform the work required. The pedal *g* is pivoted, as shown, beneath the car, the foot-piece projecting above the floor. The connection between the pedal device *g* and the bell-hammer support may be a flat band- 30 spring, *d*, or any other suitable yielding connection.

The operation of my signal device is briefly as follows: The driver, by stepping on foot-piece *e*, raises the weighted lower end of the 35 bell-hammer support *b*, so as to bring said lower end into the path of the radial projections *c*. These projections, being carried upon the rotating axle, strike successively upon the bell-hammer support, thus vibrating the bell-hammer and causing it to strike the gong *a* 40 each time one of the projections comes against the weighted end of the support. Thus the driver, by holding the foot-piece *e* depressed in the position shown, causes the bell to ring 45 continuously or until the pressure is removed from the pedal. The other set of the signaling devices consists of the gong *a'*, the bell-hammer support *b'*, the pedal *g'*, and the coiled spring *f*, forming the yielding connection between the pedal *g'* and the bell-hammer support *b'*. The radial projections *c'* are the same 50 in operation as the radial projections *c*, heretofore described. A third form of the yielding connection is shown at *h* in Fig. 2. In Figs. 55 4 and 5 the radial projections are shown upon the hub of the wagon, the gong, the pedal, and the hammer-support being placed in convenient position, as shown, so that the bell may be operated by pressing continuously 60 upon the foot-piece of the pedal.

The modifications shown in Figs. 6 and 7 require no special description, it being understood that cars of this style are always run in the same direction.

I am aware that gongs have been heretofore 65 secured to vehicles, the hammer whereof has been adjustably actuated in the movement of said vehicle by pressure exerted upon a pedal device, as is shown and described in German Patent No. 27,337, to Julius Riedel; but, so far 70 as I am aware, no device operated substantially as the herein-described invention has been heretofore made.

Having thus described my invention as embodied in several forms of mechanism, it will 75 be understood that I do not limit myself to the details of construction shown, since there are various modifications of my invention which would readily suggest themselves to those skilled in the art. I have shown the 80 lower end of the bell-hammer support weighted. It is evident that a spring might be used as the equivalent of the weight.

I claim as my invention and desire to secure by Letters Patent— 85

1. The combination, with one or more radial projections rigidly secured to the rotatory axle or hub of a vehicle, of a gong secured to the body or frame-work of the vehicle, a bell-hammer mounted on a pivoted arm and actuated to sound said gong by the pivotal movement of the arm when operated by the revolving of said radial projections, and a pedal device, also secured to the body or frame-work of the vehicle and yieldingly connected with 95 the said pivoted arm, whereby on depressing said pedal device said pivoted arm is brought into the path of the revolving radial projections and operated thereby, substantially as and for the purpose specified. 100

2. The combination, with the revolving axle or hub of a vehicle, of radial wings or projections thereon rigidly secured thereto, a pedal device, and a pivoted bell-hammer support secured to the body or frame-work of said vehicle, whereby on depressing the pedal one end of the bell-hammer support is moved into the pathway of and actuated by the rotation of the wings or radial projections as said vehicle is propelled, substantially as and for 105 the purpose specified. 110

In witness whereof I hereunto subscribe my name this 25th day of August, A. D. 1888.

JOHN B. GRIFFIN.
